Des. 198,411
Patented June 9, 1964

198,411

BOX FOR DISPLAYING MERCHANDISE

Irwin Hanopole, 33 Colonial Woods Drive,
West Orange, N.J.

Filed Apr. 6, 1962, Ser. No. 69,605

Term of patent 14 years

(Cl. D58—12.6)

The figure is a front perspective view taken from the top and one end of a box for displaying merchandise embodying my new design, the rear and opposite end being substantially the same as the front and end shown, respectively.

I claim:

The ornamental design for a box for displaying merchandise, as shown and described.
